UNITED STATES PATENT OFFICE.

FRANK F. SLOCOMB, OF PHILADELPHIA, PENNSYLVANIA.

LEATHER-STAKING MACHINE.

1,268,637.

Specification of Letters Patent. Patented June 4, 1918.

Application filed March 27, 1912. Serial No. 636,687.

To all whom it may concern:

Be it known that I, FRANK F. SLOCOMB, a citizen of the United States, residing in the city and county of Philadelphia, State 5 of Pennsylvania, have invented a new and useful Leather-Staking Machine, of which the following is a specification.

My invention consists of an improved attachment for leather-staking machines.

10 It further consists of an improved means for adjusting the leather-engaging means of the upper jaw of such machine.

It further consists of improved means for taking up wear of the journals of the 15 rollers in the upper jaw.

It further consists of other novel features of construction, all as will be hereinafter fully set forth.

The annexed drawings and the following 20 description set forth in detail one mechanical form embodying the invention, such detail construction being but one of various mechanical forms in which the principle of the invention may be used.

25 In said annexed drawings:—

Figure 1 represents a side elevation of as much of a leather-staking machine as will illustrate the application of my invention.

Fig. 2 represents a top plan view of the 30 outer end of the upper jaw of the machine and the leather-engaging rollers upon the same.

Fig. 3 represents a side view of said parts.

Fig. 4 represents a front view of the same.

35 Fig. 5 represents a top plan view of the bracket and bearings for the outer roller.

Fig. 6 represents a plan view of the bracket for the inner roller.

Fig. 7 represents a sectional detail view 40 of a bearing for the journals of the rollers.

Fig. 8 represents a side view of the end of the upper jaw of a staking machine, showing another embodiment of my invention.

45 Fig. 9 represents a top plan view of said parts.

Fig. 10 represents a front view of said parts.

Fig. 11 represents a side view of the end 50 of the upper jaw of the machine, illustrating still another embodiment of the invention.

While my improvements may be applied to several types of staking-machines, I have 55 illustrated them as applied to the machine for which Letters Patent No. 604,560, were

granted to myself and James Craig on May 24th, 1898.

Referring to the drawings, the reference 60 numeral 1 indicates the frame of the machine having the reciprocating upper and lower jaws, 2 and 3, which need not be described, being the same as those illustrated and described in said above patent. The machine has the usual breast-roll, 4, and 65 two staking-blades, 5 and 6, are supported upon the lower jaw, one adjustable in its relation to the other, longitudinally of the machine, by adjusting screws, 7, or other 70 means.

A T-shaped bracket, 8, has two longitudinal slots, 9, in its flat shank, through which pass adjusting and fastening bolts, 10, passing through the outer end of the upper jaw and having nuts, 11, and washers, 12, for 75 clamping the shank of the bracket to the under-side of the upper jaw. Two perforated ears, 13, project downward from the side-edges of the flat shank. The ends of the transverse head of the bracket have 80 slots, 14, and guide-recesses, 15, are formed in the under-sides of said ends. Conical 85 bearings, 16, have screw-threaded sockets, 17, upon their upper sides, and rectangular flanges, 18, upon the upper ends of said sockets are movable in the guide-recesses. Screw-bolts, 19, pass through the slots in the cross-head and into the socket to adjust 90 the bearings transversely to the jaw and to the machine. A roller, 20, has conical journals, 21, which fit and turn in the conical bearings, and wear on said journals and bearings may be taken up by adjusting the 95 bearings and their bolts in the slots in the cross-head.

A bracket, 22, has its shank forked to 100 form arms, 23, having longitudinal slots, 24, through which passes a bolt, 25, having a nut, 26, and which bolt also passes through the perforated ears 13 of the bracket secured to the jaw, so that the slotted arm of the forked bracket may be adjusted longitudinally in its relation to the jaw. The outer end of the forked bracket is curved downward and is formed with a cross-head 105 22*, inclined to the vertical plane and formed with slots, 27, in its ends and with rectangular guide-recesses, 28, in the forwardly and downwardly facing side. Conical bearings, 29, similar to the bearings 16 in the first-described bracket, have screw-threaded sockets, 30, and rectangular flanges 110

movable in the guide-recesses. Screw-bolts, 31, pass through the slots in the inclined cross-head and into the sockets upon the bearings. A roll, 32, is journaled with its conical journals, 33, in the latter bearings.

A screw-bolt, 34, forming an adjustable abutment is threaded in a perforation, 35, in the cross-head of the upper bracket and bears with its end in a step, 36, upon the lower bracket.

In Figs. 8, 9 and 10 is illustrated a slightly different form of my invention, in which the cross-head, 22^x, of the lower bracket is bent down into a vertical plane and a blade, 37, secured to the forward face of said cross-head by means of screw-bolts, 38, and a clamping plate, 39, the bolts passing through such clamping plates and through vertical slots, 40, in the blade, into the cross-head.

The tension members for exerting tension upon the skin to be staked,—the rollers in the form illustrated in Figs. 1 to 7, included, and the roller and blade of the form illustrated in Figs. 8, 9 and 10,—and by means of which the skin is more or less flexed over the blades according to the relative proximity of the means to each other and to the blades of the lower jaw, being adjustable longitudinally upon the upper jaw, admit of the flexure of the skin over the edge of the staking-blade being adjusted to a greater or less degree, whereby the staking action upon the skin is increased or decreased. This adjustment, as well as the longitudinal adjustment of the blades upon the lower jaw, also admits of the elements being accurately adjusted according to the thickness of the skins to be staked.

As the operation of a staking machine is well known, it is not deemed necessary to enter into a detailed description of the same. As the open jaws advance forward, the skin is inserted between them, whereupon they close and move rearward, dragging against both sides of the skin,—the rollers against the upper side and the blades against the under side. When the jaws arrive at the rear extreme of their reciprocation, they open and move forward, again grasping the skin when they arrive at the forward extreme of their movement. The operator holds the skin against the rearward drag of the jaws by clamping it between his body and the breast-roll, and shifts its position when the jaws are open.

Any wear on the journals of the rollers or their bearings may be taken up by moving the bearings inward, toward one another, so that the rollers will run true and cause the blades to act uniformly on the skins, which is of great importance in staking skins on a machine to insure uniformity of the texture of the skins.

In Fig. 11 is illustrated a slightly differ-

ent form of the upper bracket 8, illustrated in Figs. 1, 2, 3, 4 and 6, the bracket having its T-head upwardly inclined to provide oblique adjustment for the roller instead of straight vertical.

Other modes of applying the principle of my invention may be employed for the mode herein explained. Change may therefore be made as regards the mechanism thus disclosed, provided the principles of construction set forth, respectively, in the following claims are employed.

Having thus described my invention, what I claim as new and desire to secure by Letters Patent, is:—

1. In a leather staking machine, a lower jaw, a plurality of transverse staking blades upon said jaw, means for relatively adjusting the same longitudinally to said jaw, an opposed upper jaw, transverse staking members upon said upper jaw and arranged to alternate with said blades, a single adjusting member to effect the relative vertical adjustment of the upper jaw staking members, and means for relatively and longitudinally adjusting each of said staking members longitudinally to said upper jaw.

2. In a leather staking machine, a lower jaw, a plurality of transverse staking blades upon said jaw, means for relatively adjusting such blades longitudinally to said jaw, an upper jaw, transverse staking members arranged upon said jaws to alternate with said blades, means for relatively and longitudinally adjusting such members longitudinally to said jaw, means to effect the relative vertical adjustment of said staking members, a plurality of fastening devices common to said upper jaw and said staking members for securing the latter fixedly in their longitudinally adjusted position, and a transverse fastening device common to said adjusting means for said staking devices for securing the latter with respect to each other in their adjusted position.

3. In a leather staking machine, a jaw, a T-shaped bracket formed with longitudinal slots in its shank and with slots in the ends of its cross-head and having perforated ears on the sides of its shank, bolts passed through the jaw and through the slots in the shank of said bracket and having means for clamping the latter to said jaw, bearings movable on the ends of the cross-head of said jaw, bolts passed through the slots in the cross-head and engaging said bearings, a roller having its journals in said bearings, a bracket having a forked shank formed with longitudinal slots in its arms and a downwardly curved forward end formed with an inclined cross-head having slots in its ends, a bolt passed through the slots in the arms of said bracket and through the ears of said former bracket and having means for clamping said parts in adjusted

position, bearings movable on the ends of the inclined cross-head, bolts passed through the slots in said cross-head and engaging said bearings, and a staking device having 5 its journals in said bearings.

4. In a leather staking machine, a bracket formed with a cross-head having slots in its ends and guide-recesses, laterally extending bearings formed with upwardly 10 extending screw-threaded sockets having flanges movable in said guide-recesses, screw-bolts passed through the slots of the cross-head and engaging the threaded portions of 15 said sockets, and a roller having at its extremities journals mounted in said bearings.

5. In a leather-staking machine, an upper jaw, a bracket secured thereto and having a plurality of longitudinally extending slots therein, fastening devices common to the 20 slots of said bracket and said upper jaw, depending lugs on the sides of said bracket, a staking device mounted in the forward portion of said bracket, a second bracket located below said bracket and having forked arms 25 provided with slots therein, fastening devices common to said brackets, and a staking device secured to the forward extremity of said lower bracket.

6. In a leather-staking machine, a jaw 30 having a bracket secured thereto and provided in its outer extremities with elongated slots therein, guide recesses on the under side of said bracket, laterally extended bearings having upwardly projecting screw 35 threaded sockets therein, flanges on said sockets adapted to be guided in said recesses, screw-threaded bolts common to said slots and threaded sockets, and a staking roller having journals at its extremities, said journals being rotatably mounted in said bearings.

7. In a leather-staking machine, a jaw having a bracket secured thereto and provided at its outer under portions with guide 45 recesses therein, laterally extending bearings, having upwardly projecting screw-threaded sockets, flanges on said sockets adapted to be guided in said recesses, adjustable fastening devices common to said 50 bracket and sockets, and a staking roller having journals at its extremities, said journals being rotatably mounted in said bearings.

8. In a leather-staking machine, a jaw 55 having a bracket secured thereto and provided in its outer forward extremities with elongated slots therein, guide recesses on the under side of said bracket, laterally extended bearings having upwardly projecting 60 screw threaded sockets therein, flanges on said sockets adapted to be guided in said recesses, screw-threaded bolts common to said slots and threaded recesses, a staking roller having journals at its extremities, said journals being rotatably mounted in said bear-

ings, and means for securing said brackets with respect to each other in their longitudinally adjusted position, the forward end of said lower bracket being inclined downwardly and outwardly.

9. In a leather staking machine, an upper jaw, a substantially T shaped bracket secured thereto, and having in its shank a longitudinally extending slot, fastening devices common to said jaw and shank and permitting longitudinal adjustment of the latter, apertured ears on said shank, a second forked bracket below said former bracket and adjustable with respect thereto, fastening devices common to said ears and second 75 brackets, an adjustable abutment to vary the relative position of the forward portions of said brackets, and staking devices secured in the forward portions of said brackets.

10. In a leather staking machine, an upper 80 jaw, a substantially T shaped bracket secured thereto, and having in its shank a longitudinally extending slot, fastening devices common to said jaw and shank and permitting longitudinal adjustment of the latter, apertured ears on said shank, a second forked bracket below said former bracket and adjustable with respect thereto, fastening devices common to said ears and second 85 brackets, an adjustable abutment cooperating with said second bracket to limit the movement thereof toward the upper jaw, and staking devices secured in the forward portions of said brackets, in combination with a lower jaw, staking devices on said lower jaw, and means for adjusting the staking devices of said lower 90 jaw, with respect to the staking devices carried by said upper jaw.

11. In a leather staking machine, a staking jaw, a bracket secured thereto, detachable and adjustable bearings secured to the outer under portions of said bracket, said bearings being juxtaposed to each other in alinement and having their widest portions 105 facing each other, screw threaded sockets extending upwardly from said bearings, threaded fastening devices common to said sockets and the extremities of said bracket, a staking roll located below said bracket and between said bearings, and journals on said roll adapted to fit and enter said bearings.

12. In a leather-staking machine, a staking jaw, a bracket secured thereto, detachable and adjustable bearings secured to the 110 outer under portions of said bracket, said bearings being juxtaposed to each other in alinement, screw threaded sockets extending upwardly from said bearings, threaded fastening devices common to said sockets and 115 the extremities of said bracket, a staking roll located below said bracket and between said bearings and journals on said roll adapted to fit and enter said bearings, in combination with a second bracket below 120 125 130

- said former bracket, means for enabling said latter bracket to be longitudinally adjusted with respect to said former bracket, and a staking device for said bracket.
- 5 13. In a leather-staking machine, a jaw, a substantially T shaped bracket secured thereto and provided at its inner end with elongated slots and at its outer extremities also with elongated slots therein, recesses on 10 the forward under sides of said bracket, laterally extending bearings having upwardly projecting screw threaded sockets therein, flanges on said sockets adapted to be guided in said recesses, threaded bolts 15 common to said slots and threaded recesses, a staking roller having journals at its extremities, said journals being rotatably mounted in said bearings, a lower bracket longitudinally adjustable with respect to 20 said upper bracket, means for securing said brackets with respect to each other in their longitudinally, adjustable positions, the forward end of said lower bracket being inclined downwardly and outwardly, a staking 25 device secured in the forward extremity of said lower bracket, and a screw threaded bolt adjustably mounted in a cross head of the first mentioned bracket and having its end bearing upon the lower bracket.
- 30 14. In a leather staking machine, a staking jaw, a bracket adjustably carried thereby, a staking tool carried by said bracket, a second bracket adjustably carried by said first bracket, a staking tool on the 35 second bracket, and an adjustable abutment

carried by one bracket and engaging the other bracket to limit relative movement of the forward portion of said brackets.

15. In a leather staking machine, a staking jaw, a bracket thereon having laterally extending guides, journals adjustable in said guides, a roller mounted in said journals, a second bracket having its inner end forked and adjustably connected with said first bracket, and having a cross head 45 provided at its forward end with lateral guides, journals adjustable in said cross head guides, a roller mounted in said last named journals, and an adjustable abutment carried by one bracket and bearing against 50 the other bracket.

16. In a leather staking machine, a staking jaw, a bracket thereon having laterally extending guides, journals adjustable in said guides, a roller mounted in said 55 journals, a second bracket having its inner end forked and adjustably connected with said first bracket, and having a cross head inclined to the vertical and provided at its forward end with lateral guides, journals 60 adjustable in said cross head guides, a roller mounted in said last named journals, and an adjustable abutment carried by one bracket and bearing against the other bracket.

FRANK F. SLOCOMB.
